TIME-INDICATING FACE FOR A HOROLOGUE

Shigeru Fukumoto, Nishinomiya, Japan, assignor to
Kabushiki Kaisha Suncrux Research Office, Kobe,
Japan

Filed Oct. 13, 1971, Ser. No. 189,065

Claims priority, application Japan Apr. 15, 1971

Term of patent 14 years

Int. Cl. D10—07

U.S. Cl. D42—1 B

Fig. 1

*Fig. 2*FIG. 1 is a side elevational view of a time-indicating face for a horologe showing my new design, all sides being identical.

FIG. 2 is an enlarged top plan view thereof, the bottom being substantially identical thereto.

The drawings are shaded for color contrast.

I claim:

The ornamental design for a time-indicating face for a horologe, as shown and described.
